SYNCHRONOUS ELECTRIC MOTOR
STRUCTURE

Arthur B. Poole, Bristol, Conn., assignor to The
E. Ingraham Company, Bristol, Conn., a cor-
poration of Connecticut

Original application December 3, 1937, Serial No.
177,839. Divided and this application April 29,
1938, Serial No. 204,933

10 Claims. (CL 172—278)

This invention relates to an improvement in synchronous-electric motor-structures, and more especially to an improvement in synchronous-electric motor-structures of the character employed in the propulsion of clocks and other time-instruments; and constitutes a division of my co-pending application Serial No. 177,839, filed December 3, 1937.

One of the objects of the present invention is to provide a superior synchronous-electric motor-structure having an improved construction and arrangement of parts, whereby current may be supplied to the energizing-coil associated with a field-structure sealed within a substantially oil-tight casing.

Another object of the present invention is to provide a superior synchronous-electric motor-structure of the type having an enclosed energizing-coil, with a superior construction and arrangement of terminal-fittings through which electric current may be supplied to the enclosed energizing-coil with an enclosed field-structure.

With the above and other objects in view, as will appear to those skilled in the art from the present disclosure, this invention includes all features in the said disclosure which are novel over the prior art and which are not claimed in any separate application.

In the accompanying drawing, in which a preferred embodiment of the invention is shown for illustrative purposes:

Fig. 1 is a view in front-end elevation of a synchronous-electric motor-structure embodying the present invention;

Fig. 2 is a view thereof in side elevation;

Fig. 3 is a view of the motor-structure shown in axial section and taken on the line 3—3 of Fig. 1;

Fig. 4 is a fragmentary section taken on the line 4—4 of Fig. 2, one of the terminal-fitting units being shown in side elevation;

Fig. 5 is a perspective view of an outer bushing detached from one of the terminal-assemblies;

Fig. 6 is a perspective view of one of the insulator-bushings detached; and

Fig. 7 is a similar perspective view of one of the terminal-receiving bushings detached.

According to the illustrative embodiment of the present invention shown on the drawing, a cup-shaped pole-unit is employed which constitutes a part of a hollow field-structure and comprises a relatively-deep outer cup-shaped member 10 and a relatively-shallow cup-shaped inner member 11 tightly fitted within the said outer member 10. The said cup-shaped pole-unit is constructed to

receive a disk-like pole-unit comprising an outer disk 12 and an inner disk 13; the said disk-like pole-unit being fitted within the open end of the outer cup-shaped member 10 of the cup-shaped pole-unit to bear against the outer edge of the inner cup-shaped member 11 of the said cup-shaped pole-unit, as shown in Fig. 3. The outer and inner cup-shaped members 10 and 11 comprising the cup-shaped pole-unit and the inner and outer disks 12 and 13 comprising the disk-like pole-unit, are composed of suitable magnetic material, such, for instance, as soft iron, silicon steel, or the like.

For the purpose of rigidly securing the disk-like pole-unit in position within the outer cup-shaped member 10, the periphery of the said outer member 10 of the cup-shaped pole-unit may be indented at spaced intervals as at 14 (Fig. 3) to displace metal over the rear face of the outer member 12 of the disk-like pole-unit.

Projecting rearwardly from the end-wall of

the cup-shaped pole-unit is a circular series of bar-like salient poles 15 formed of suitable magnetic material and arranged in alternation with a circular series of bar-like salient poles 16 which are presented oppositely thereto from the disk-like pole-unit in the manner fully described in the above-identified co-pending application. Shading-disks 17 and 18 formed of copper or other suitable high electro-conductive material, and having the form and construction fully described in said co-pending application, are shown in Fig. 3. The said shading-disks are constructed and arranged to produce a rotating-field effect.

Extending around the exterior of the circular series of salient poles 15 and 16 within the cup-shaped pole-unit and forming a part of the field-energizing system of the synchronous motor, is a ring-like energizing-coil 19 from the rear face of which respectively adjacent the inner and outer peripheries, insulated terminal-wires 20 and 21 extend transversely through a radial slot 18a in the shading-disk 18.

Centrally arranged with respect to the annular series of salient poles 15 and 16, is a rotor-unit which, as explained in the above-identified co-pending application, preferably comprises a rotor-hub 22 constructed of brass or the like, a pair of corresponding but oppositely-facing cup-shaped rotor-elements 23—23 which are preferably formed of permanent magnet steel or its equivalent and spaced from each other by a salient-pole rotor-element 24 which may be con-

20

25

veniently made of soft iron or other non-permanent magnetic material.

The rotor-hub 22 of the rotor-elements 23 and 24 is mounted with freedom for relative rotation upon an arbor 25 and carries a pinion 26. The said pinion being the first member of a reducing gear-train including a compound gear 27-28, compound gear 29-30, and a driven gear (not shown) which is secured to a power-output 10 shaft (not shown).

All of the above-described parts are enclosed within an oil-retaining housing comprising a relatively-deep cup-shaped housing-member 31 and a flanged cap-member 32 which latter fits over 15 the cylindrical wall of the cup-shaped housing-member 31. The construction and arrangement of the housing, as it is described in the copending application identified herein, is such, that oil may be introduced and retained in the housing 20 and it may move substantially-freely about the interior of the housing and about the said parts mounted therein. Sealing arrangements are also provided for the housing to prevent escape of the oil therefrom and as part of these provisions the 25 cap-member 32 is preferably soldered or otherwise sealed to the cup-shaped member 31 to provide substantially oil-tight housing.

As shown in Figs. 1 and 4, two terminal-assemblies of improved construction, comprising 30 terminal-fittings, are mounted in the cylindrical wall of the relatively-deep cup-shaped housing-member 31 and pass therethrough into a portion of the housing in which oil is held. The said terminal-assemblies being preferably identical in 35 construction, a description of one will serve for both in the present embodiment of the invention. In the form shown in detail in Figs. 4, 5, 6, and 7, each of the terminal-assemblies comprises an outer bushing 33, an inner bushing 34, and an 40 intermediate bushing 35, all of said bushings being constructed of suitable materials for their respective purposes to be presently described.

The outer bushing 33 is preferably formed of brass or other metal which may be conveniently 45 soldered to the adjacent portion of the periphery of the cup-shaped housing-member 31, and has its major portion extended into the interior of the said housing-member to a degree sufficient to bring an annular flange 33^a at its outer end into 50 seating engagement with the outer surface of the said housing-member 31, as is particularly well shown in Fig. 4.

Tightly fitting into the axial passage in the outer bushing 33 is the intermediate bushing 35 which is preferably composed entirely of insulating 55 material such, for instance, as Bakelite, indurated fiber, etc. The said intermediate bushing is preferably constructed so as to have a relatively-long inner stem 35^a, a relatively-short intermediate neck 35^b, and a head or flange-portion 60 35^c. The inner face of the neck 35^b of the bushing 35 is preferably firmly seated against the outer face of the outer bushing 33, as shown.

The inner bushing 34, above referred to, may 65 be aptly termed a terminal-wire-receiving sleeve or bushing, and is preferably formed of brass or other suitable readily-solderable electroconductive material, and includes a relatively-long 70 tubular shank which fits tightly into the axial passage in the intermediate bushing 35 and is also provided at its outer end with a head-portion 34^a which seats against the outer face of the flange 35^c of the said intermediate bushing.

The bare outer portion of either the terminal- 75 wire 20 or the terminal-wire 21, as the case may

be, is passed outwardly through the axial passage in the inner bushing 34, and is preferably deflected laterally so as to lie in close proximity to the outer face of the said inner bushing.

After the bared portions of the terminal-wires 5 20 and 21 have been threaded outwardly through their respective inner bushings 34, the bared ends of supply-wires 36 and 37 respectively may be soldered thereto as at 38. The said soldering not only results in the direct interconnection of 10 the wires 20-36 and 21-37, but also anchors all of the said wires directly to their respective inner bushings 34. Furthermore, the solder at 38 serves to seal the axial passage through both of the inner bushings and thus guards against the outer 15 leakage of oil from within the casing provided by the members 31 and 32.

Thus, by means of the construction and arrangement of parts above described, a simple, reliable and effective electrical connection is provided 20 between the terminal-wires of the energizing-coil 19 and external supply-wires such, for instance, as 36 and 37. The connections thus provided are not only electrically effective, but are also of great mechanical strength, so that stresses 25 applied to the exterior supply-wires 36 and 37 are effectively resisted without interrupting the electrical connection.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A synchronous-electric motor-structure including in combination: an oil-retaining housing; a field-structure enclosed within the said housing; an energizing-coil also enclosed within the said housing in position to apply magnetic-flux to the said field-structure; a rotor also enclosed within the said housing and positioned to be 40 synchronously rotated by the magnetic-flux applied to the said field-structure by the said energizing-coil; a plurality of terminals mounted in the said housing, and each having a passage extending therethrough from the interior to the exterior of the said housing; a plurality of terminal-wires connected to the said energizing-coil, each of said terminal-wires leading from the said energizing-coil outwardly through the passage in one of said terminals to the exterior of 50 the said housing; the said housing being constructed and arranged for substantially-free movement of oil within its interior and about all of the said parts mounted therein; and the said housing being also substantially-sealed against 55 escape of oil, each of the said terminals being mounted in fluid-tight relation to the housing, and the sealing arrangements also including a sealing-body secured to each of the terminals and about the terminal-wire passing therethrough, 60 to close and oil-tightly seal the passage in each of the terminals, and to anchor one of the terminal-wires to each of the said terminals.

2. A synchronous-electric motor-structure including in combination: an oil-retaining housing; 70 a field-structure enclosed within the said housing; an energizing-coil also enclosed within the said housing in position to apply magnetic-flux to the said field-structure; a rotor also enclosed within the said housing and positioned to be 75

synchronously rotated by the magnetic-flux applied to the said field-structure by the said energizing-coil; a plurality of terminals mounted in the said housing, and each having a passage extending therethrough from the interior to the exterior of the said housing; a plurality of terminal-wires connected to the said energizing-coil, each of said terminal-wires leading from the said energizing-coil outwardly through the passage in one of said terminals to the exterior of the said housing; an electric supply-wire leading to the outer end of each of the said terminals, the said housing being constructed and arranged for substantially-free movement of oil within its interior and about all of the said parts mounted therein; and the said housing being also substantially-sealed against escape of oil, each of the said terminals being mounted in fluid-tight relation to the housing, and having its outer end-portion composed of solder-receptive material, and the sealing arrangements also including bonds of solder each uniting one of the terminals-wires with one of the supply-wires and jointly anchoring the same to the solder-receptive outer end-portion of one of the terminals, one of the said bonds of solder closing and oil-tightly sealing the passage in each of the said terminals.

3. A synchronous-electric motor-structure including in combination: an oil-retaining housing; a field-structure enclosed within the said housing; an energizing-coil also enclosed within the said housing in position to apply magnetic-flux to the said field-structure; a rotor also enclosed within the said housing and positioned to be synchronously rotated by the magnetic-flux applied to the said field-structure by the said energizing-coil; a plurality of terminals mounted in the said housing, each of said terminals including a bushing having a passage extending therethrough from the interior to the exterior of the said housing; a plurality of terminal-wires connected to the said energizing-coil, each of said terminal-wires leading from the said energizing-coil outwardly through the passage in one of the said bushings to the outer end-portion of that bushing; a plurality of electric-supply wires respectively leading to the outer end-portions of the said bushings; the said housing being constructed and arranged for substantially-free movement of oil within its interior and about all of the said parts mounted therein; and the said housing being also substantially-sealed against escape of oil, each of the said terminals being mounted in fluid-tight relation to the housing, and the bushing of each terminal having its outer end portion composed of solder-receptive material, and the sealing arrangements also including bonds of solder each permanently uniting one of the terminal-wires with one of the supply-wires and jointly permanently anchoring the same to the solder-receptive outer end-portion of one of the said bushings, one of the said bonds of solder closing and oil-tightly sealing the passage in the bushing of each of the said terminals.

4. A synchronous-electric motor-structure including in combination: an oil-retaining housing; a field-structure enclosed within the said housing; an energizing-coil also enclosed within the said housing in position to apply magnetic-flux to the said field-structure; a rotor also enclosed within the said housing and positioned to be synchronously rotated by the magnetic-flux applied to the said field-structure by the said energizing-coil; a plurality of terminal-assemblies mounted in the said housing and each having a

passage extending therethrough to provide communication between the interior and the exterior of the said housing; a plurality of terminal-wires connected to the said energizing-coil leading therefrom outwardly respectively through the passage in one of the said terminal-assemblies to the exterior of the said housing; the said housing being constructed and arranged for substantially-free movement of oil within its interior and about all of the said parts mounted therein; and the said housing being also substantially-sealed against escape of oil, each of the said terminals being mounted in fluid-tight relation to the housing, the sealing arrangements including a member of each of the said terminal-assemblies arranged in fluid-tight relation to the said housing, and also including a sealing-body secured to another member of each of the terminal-assemblies and about the terminal-wire passing therethrough, to close and oil-tightly seal the passage in the said terminal-assembly and to anchor one of the terminal-wires to each of the said terminal-assemblies.

5. A synchronous-electric motor-structure including in combination: an oil-retaining housing; a field-structure enclosed within the said housing; an energizing-coil also enclosed within the said housing in position to apply magnetic-flux to the said field-structure; a rotor also enclosed within the said housing and positioned to be synchronously rotated by the magnetic-flux applied to the said field-structure by the said energizing-coil; a plurality of terminal-assemblies mounted in the said housing and each having a passage extending therethrough to provide communication between the interior and the exterior of the said housing; a plurality of terminal-wires connected to the said energizing-coil leading therefrom outwardly respectively through the passage in one of the said terminal-assemblies to the exterior of the said housing; the said housing being constructed and arranged for substantially-free movement of oil within its interior and about all of the said parts mounted therein; and the said housing being also substantially-sealed against escape of oil, each of the said terminals being mounted in fluid-tight relation to the housing, the sealing arrangements including an insulator-bushing of each terminal-assembly oil-tightly fitted about the outer wall of an inner bushing of each terminal-assembly and means supporting the insulator-bushing of each terminal-assembly and having fluid-tight relation to the said housing, the said sealing arrangements also including a sealing-body secured to the inner bushing of each terminal-assembly adjacent the exterior end thereof and to the terminal-wire passing through the said inner bushing, to close and oil-tightly seal the passage in the said inner bushing and to anchor one of the terminal-wires to the inner bushing of each of the said terminal-assemblies.

6. A synchronous-electric motor-structure including in combination: an oil-retaining housing; a field-structure enclosed within the said housing; an energizing-coil also enclosed within the said housing in position to apply magnetic-flux to the said field-structure; a rotor also enclosed within the said housing and positioned to be synchronously rotated by the magnetic-flux applied to the said field-structure by the said energizing-coil; a plurality of terminal-assemblies mounted in the said housing and each having a passage extending therethrough to provide communication between the interior and the ex-

terior of the said housing; a plurality of terminal-wires connected to the said energizing-coil leading therefrom outwardly respectively through the passage in one of the said terminal-assemblies to the exterior of the said housing; the said housing being constructed and arranged for substantially-free movement of oil within its interior and about all of the said parts mounted therein; and the said housing being also substantially-sealed against escape of oil, each of said terminal-assemblies comprising an outer bushing mounted in an opening formed in the wall of said housing and forming therewith an oil-tight seal around the edge of the said opening; an insulator-bushing mounted within and forming an oil-seal with the said outer bushing; and an inner bushing, through which one of the said terminal-wires extends, mounted within and forming an oil-tight seal with the inner wall of said insulator-bushing, said inner bushing being constructed of metal at its outer end; a plurality of electric supply-wires respectively leading to the metallic outer ends of the said inner bushings; and the sealing arrangements also including bonds of solder each uniting one of the terminal-wires with one of the supply-wires and jointly anchoring the same to the metallic outer end of one of the inner bushings, one of the said bonds of solder closing and oil-tightly sealing the passage in the inner bushing of each of the said terminal-assemblies.

7. A synchronous-electric motor-structure including in combination: an oil-retaining housing; a field-structure enclosed within the said housing; an energizing-coil also enclosed within the said housing in position to apply magnetic-flux to the said field-structure; a rotor also enclosed within the said housing and positioned to be synchronously rotated by the magnetic-flux applied to the said field-structure by the said energizing-coil; a plurality of terminal-assemblies mounted in the said housing and each having a passage extending therethrough to provide communication between the interior and the exterior of the said housing; the said housing being constructed and arranged for substantially-free movement of oil within its interior and about all of the said parts mounted therein; and the said housing being also substantially-sealed against escape of oil, each of the said terminal-assemblies comprising an outer bushing mounted in an opening formed in the wall of said housing, the said outer bushing being provided with a flange in abutment with the housing-wall around the edges of said opening and soldered to the said housing-wall to provide an oil-tight joint therebetween; an insulator-bushing mounted in and forming an oil-tight seal with the said outer bushing; and an inner bushing constructed of metal mounted in and forming an oil-tight seal with said insulator-bushing; a plurality of terminal-wires connected to the said energizing-coil, the said terminal-wires leading from the said energizing-coil outwardly through the said inner bushings respectively to the outer ends thereof; a plurality of electric-supply wires respectively leading to the outer ends of the said inner bushings; and the sealing-arrangements also including bonds of solder each uniting one of the terminal-wires with one of the supply-wires and jointly anchoring the same to the metallic outer end of one of the inner bushings, one of the said bonds of solder closing and oil-tightly sealing the passage in the inner bushing of each of the said terminal-assemblies.

8. A synchronous-electric motor-structure including in combination: an oil-retaining housing; a field-structure enclosed within the said housing; an energizing-coil also enclosed within the said housing in position to apply magnetic-flux to the said field-structure; a rotor also enclosed within the said housing and positioned to be synchronously rotated by the magnetic-flux applied to the said field-structure by the said energizing-coil; a plurality of terminal-assemblies mounted in the said housing and each having a passage extending therethrough to provide communication between the interior and the exterior of the said housing; the said housing being constructed and arranged for substantially-free movement of oil within its interior and about all of the said parts mounted therein; and the said housing being also substantially-sealed against escape of oil, each of said terminal-assemblies comprising a metallic outer bushing mounted in the housing in fluid-tight relation thereto; an insulating-bushing projecting outwardly and inwardly beyond the outer and inner ends respectively of said outer bushing; and an inner metallic bushing projecting outwardly beyond the outer end of said insulating-bushing and terminating at its inner end within said insulating-bushing; an electric-supply wire leading to the outer end of each inner bushing; and the sealing-arrangements also including bonds of solder each uniting one of the terminal-wires with one of the supply-wires and jointly anchoring the same to the metallic outer end of one of the inner bushings, one of the said bonds of solder closing and oil-tightly sealing the passage in the inner bushing of each of the said terminal-assemblies.

9. A synchronous-electric motor-structure including in combination: an oil-retaining housing; a hollow field-structure enclosed within the said housing and having an end-wall adjacent to and spaced laterally from the end-wall of said housing; an energizing-coil mounted within the hollow field-structure to apply magnetic-flux thereto; a rotor positioned to be synchronously rotated by the magnetic-flux applied to the said field-structure by the said energizing-coil; a plurality of terminals mounted in the said housing between the said end-wall of the housing and the end-wall of the hollow field-structure adjacent thereto; each of said terminals having a passage extending therethrough to provide communication between the interior and the exterior of the said housing; a plurality of terminal-wires connected to the said energizing-coil, said terminal-wires leading from said energizing-coil past the said end-wall of the said hollow field-structure and outwardly through the passages respectively in the said terminals to the outer ends of said terminals; electric-supply wires leading to the outer ends of the said terminals respectively; the said housing being constructed and arranged for substantially-free movement of oil within its interior and about all of the said parts mounted therein; and the said housing being also substantially-sealed against escape of oil, each of the said terminals being mounted in fluid-tight relation to the housing, and the sealing arrangements also including a sealing-body secured to each terminal and uniting the terminal-wire passing therethrough with one of the supply-wires and jointly anchoring the same to the terminal, each sealing-body closing and oil-tightly sealing the passage in one of the said terminals.

10. A synchronous-electric motor-structure including in combination: an oil-retaining housing; a field-structure enclosed within the said housing; an energizing-coil also enclosed within the said housing to apply magnetic-flux to the said field-structure; a rotor positioned within the said housing to be synchronously rotated by the magnetic-flux applied to the said field-structure; a terminal mounted in the said housing and having a passage extending from the interior to the exterior of the said housing; a terminal-wire leading from the said energizing-coil through the said passage to the exterior of the said housing; the said housing being constructed and arranged

for substantially-free movement of oil within its interior and about all of the said parts mounted therein; and the said housing being also substantially-sealed against escape of oil, each of the said terminals being mounted in fluid-tight relation to the housing, and the sealing arrangements also including means permanently secured to the terminal at the outer end thereof and also permanently secured about the terminal-wire passing therethrough, to permanently close and oil-tightly seal the passage in the said terminal and to rigidly unite the terminal-wire to the said terminal. 5 10

ARTHUR B. POOLE.
